UNITED STATES PATENT OFFICE.

CARL P. DIETZ, OF MILWAUKEE, WISCONSIN.

TEMPORARY BINDER.

Application filed April 4, 1922. Serial No. 549,491.

To all whom it may concern:

Be it known that I, CARL P. DIETZ, a citizen of the United States, and resident of Milwaukee, in the county of Milwaukee and State of Wisconsin, have invented certain new and useful Improvements in Temporary Binders; and I do hereby declare that the following is a full, clear, and exact description thereof.

10 The invention relates to temporary binders.

The primary object of the invention is the provision of a temporary binder which may be manipulated with especial convenience for the removal of individual leaves or the insertion thereof.

15 The retainers may be readily threaded thru apertures in the leaves and thru grommets in the cover, and their resilient character readily facilitates their deformation, so that the engagement of the retainers with the loops may be accomplished quickly. The pointed ends of the retainers contribute to the facile centering of the retainers in the holes. In securing position, they are reliable and adapted to withstand such force as they might ordinarily encounter without danger of detachment and separation of parts.

20 30 A feature is the ease of manufacture of the device which is composed of a minimum number of parts of simple construction.

With the above and other objects in view which will appear as the description proceeds, my invention resides in the novel construction, combination and arrangement of parts substantially as hereinafter described and more particularly defined by the appended claims, it being understood that such 35 changes in the precise embodiment of the herein disclosed invention may be made as come within the scope of the claims.

In the accompanying drawing, I have illustrated one complete example of the physical embodiment of the present invention constructed according to the best mode I have so far devised for the practical application of the principles thereof, and in which:

40 50 Figure 1 is a plan of the device in unfolded position.

Figure 2 is a cross section on the line 2—2 thereof.

55 Figure 3 is a similar plan of the alternative modification, and

Figures 4 and 5 are cross sections on the

line 4—4 and 5—5 of Figure 3, respectively.

Back 10 is provided with a pair of supports 11 directed therethrough, and clamped by their inturned ends 12 on to the back. 60 Retainers 13 are provided with eyes 14 pivoted on supports 11. The retainers are thin and flexible, and substantially semi-circular in shape. They terminate in points 15 adapted to be threaded readily through 65 openings in sheets of paper, and through grommets 16 on cover 17. By the exertion of slight pressure by the fingers, the ends 15 may be engaged under loops 18 directed through cover 10 and secured by a clinching portion 19. The cover 17 is capable of free movement on retainers 13, and the dotted lines in Figure 2 indicate its closed position. The retainers 13 may be readily removed from loops 18 and thus cover 70 17 may be released and leaves may be withdrawn or added. Thus the binder may be manipulated rapidly.

In the modification shown in Figures 3 to 5 inclusive, back 20 is provided at its 80 edges with beads 21 and 22, enveloping wires 23 and 24, the beads being cut away as shown at 25, as is also back 20 at 26, to permit the free pivotal movement of retainer 27, the eye 28 of which is rotatable on 85 wire 24. Retainer 27 is provided with a point 29 engageable under wire 23, the back 20 being cut away as at 30 to permit the insertion of end 29 which may be inserted or withdrawn by the mere deflection of resilient retainer 27.

The invention is not limited to a resilient retainer 27, but if desired, the retainer may be made rigid and back 20 may be made resilient. The retainer is adapted to be 95 threaded through openings 31 in leaves 32, and an inner binding strip 33 is secured to back 20 and to covers 34, the strip being cut away to permit free action of eye 28 and retainer 27. Outer binding strip 35 is also 100 secured to back 20 and covers 34, so that they have hinged movement and are capable of moving into the position shown in dotted lines in Figure 4. The upper and lower edges of back 20 are bent inwardly providing reinforcing folds 36, giving the back 105 transverse strength.

It is not essential that the retainer have an eye 14. The retainer may be entirely detachable, a loop 18 being provided for each 110 end. This construction would facilitate the assembly of the retainer with the back and

cover and would be releasable with especial convenience, either end being disengaged from the loop.

I claim:

- 5 1. A temporary binder for perforated leaves comprising a back portion having rolled cylindrical edges cut out at points along their length, a wire carried within said cylindrical portions, and retainers having their ends movably positioned within the cutout portion and held beneath said wires, one end of each of said retainers and the adjacent portion of the corresponding wire being adapted for a slight relative motion, whereby such end is detachably held.
- 10 2. A temporary binder for perforated leaves comprising a back portion having
- 15 2. A temporary binder for perforated leaves comprising a back portion having

rolled cylindrical edges cut out at points along their length, a wire carried within said cylindrical portions, and retainers having their ends movably positioned within 20 the cutout portion and held beneath said wires, one end of each of said retainers and the adjacent portion of the corresponding wire being adapted for a slight relative motion, whereby such end is detachably 25 held.

In testimony that I claim the foregoing I have hereunto set my hand at Milwaukee, in the county of Milwaukee and State of Wisconsin.

CARL P. DIETZ.
